CLAIM

The ornamental design for a caulking tube adaptor, as shown and described.

DESCRIPTION

FIG. 1 is a front elevational view of the caulking tube adaptor.

FIG. 2 is a rear elevational view thereof;

FIG. 3 is a left side view thereof;

FIG. 4 is a right side view thereof;

FIG. 5 is a left side front perspective view thereof;

FIG. 6 is a left side rear perspective view thereof;

FIG. 7 is a right side, front perspective view thereof; and,

FIG. 8 is a right, side, rear perspective view thereof.
